APPARATUS FOR COATING CABLES

Elmer J. Larsen, Parkville, and Charles W. Ruth,
Baltimore, Md., assignors to Western Electric
Company, Incorporated, New York, N. Y., a
corporation of New York

Application June 3, 1950, Serial No. 165,966

5 Claims. (Cl. 118—405)

1

This invention relates to apparatus for coating cables, and more particularly to apparatus for coating insulated cables before a lead sheath is extruded around the cable.

Telephone cables which are buried underground for transmitting telephone messages over long distances may include a cable core enclosed in an insulating jacket and an outer lead sheath to make the cable air-tight and moisture tight. Predetermined lengths of such cables may be manufactured by passing the core through apparatus designed to extrude a jacket of insulating material around the core and then passing the insulated core continuously and directly through an apparatus designed to continuously extrude a lead sheath around an insulated core. It is desirable to coat the insulating jacket of the cable with a soft, plastic compound before the lead sheath is extruded around the jacket. Heretofore, no satisfactory apparatus has been developed to apply a uniform coating around the jacket of a cable being advanced to and through lead sheath extruding apparatus.

An object of the invention is to provide new and improved apparatus for coating cables.

Another object of the invention is to provide new and improved apparatus for coating insulated cable cores being advanced to and through lead extruding apparatus.

An apparatus illustrating certain features of the invention for coating insulated cables may include a chamber for receiving a continuous supply of a coating compound and having entrance and exit openings through which a cable to be coated may be advanced, means for draining any excess compound from the chamber, and means communicating with the chamber through which the cable may pass for circulating the coating compound from the exit port thereof in contact with the cable a predetermined distance and back to the draining means.

Other objects and advantages of the invention appear from the following detailed description of an apparatus forming a specific embodiment thereof, when read in conjunction with the appended drawings, in which:

Fig. 1 is an elevation of an apparatus embodying certain features of the invention for coating a cable core advancing to extruding apparatus;

Fig. 2 is a transverse section taken along line 2—2 of Fig. 1;

Fig. 3 is a transverse section taken along line 3—3 of Fig. 1;

Fig. 4 is a transverse section taken along line 4—4 of Fig. 1, and

Fig. 5 is a transverse section taken along line 5—5 of Fig. 1.

Referring now in detail to the drawings, and more particularly to Fig. 1, there is shown a coating unit 10 for applying a coating 11 of a

2

suitable sealing compound around a cable 13 advanced (by means not shown) to and through a lead extruding apparatus 15 designed to extrude a lead sheath 16 around the coated core.

5 The cable 13 includes a core 18 surrounded by an insulating jacket 20, which may be made of various insulating compounds such as rubber or rubber compounds, or various thermoplastic insulating compounds such as polyethylene (polymerized ethylene).

The coating unit 10 includes an outer tank 23 having entrance and exit openings 24 and 25, respectively, through which the cable 13 may be advanced, and an opening 26 in the bottom thereof which communicates with a duct 28. A tank 30, substantially smaller in length, width and height than the tank 23, is positioned in the tank 23 so that a space exists between the sides, bottom and one end of the tank 30 and the adjacent sides, end and bottom of the tank 23. The right hand end of the tank 30, as viewed in Fig. 1 is open and abuts an end plate 31 of the outer tank 23 so that the exit opening 25 communicates with the tank 30.

25 A liquid coating compound is supplied continuously to a trough 33 by a pipe 34 connected to a circulating pump and pipe system (not shown) and discharges from the trough 33 into the inner tank 30. The compound is supplied to the trough 33 at such a rate that the tank 30 is maintained completely full of the compound, and the excess compound flows over the sides and ends of the tank 30 into the outer tank 23 and drains therefrom into the duct 28 which conveys the excess compound to a tank (not shown) in which a supply of the coating compound is maintained. A sliding door 35 may be moved upwardly manually to drain compound through an opening 36 provided in the inner tank 30 to empty the tank 30 into the tank 23 and thence into the duct 28 when it is desirable to drain the tank 30. The entrance end of the tank 30 is provided with a wiping block 37, which may be made of rubber or other suitable resilient material, designed to fit neatly around the cable 13 and prevent any foreign substance which may be on the cable from entering the inner tank 30.

An elongated inner pipe 40 (Figs. 1 and 4) has a flange 41 on one end thereof which is secured to the end plate 31 by bolts 42—42 so that the pipe 40 communicates with the exit 25 of the tank 30. An outer pipe 44, larger in diameter than the pipe 40, is secured to the flange 41 concentrically with respect to the pipe 40. The pipe 44 is somewhat shorter than the pipe 40, and spacers 45—45 equally spaced about the pipe 40 position the ends of the pipes 40 and 44 concentrically with respect to one another. The pipe 44 is designed to fit neatly into an elongated tube 48 screwed into an annular core tube holder 50 seated in the end of

an elongated tubular barrel 51 forming part of the lead press 15. The pipes 40 and 44 are of such length that when the pipe 44 extends into the tube 48 a short distance, the free end of the inner pipe 40 is positioned close to an annular core tube 55 positioned on the end of the core tube holder 50. Spacers 53—53, similar to the spacers 45—45, are mounted on and equally spaced about the pipe 40 and serve to align the pipe 40 concentrically within the tube 48. Spacers 53—53 (Fig. 5) 10 are equally spaced about the end of the pipe 40 position the pipe 40 concentrically with respect to the tube 48 of the lead press 15.

The core tube 55 (Fig. 1) coacts with an annular forming die 56 to form an extrusion orifice 57 in the lead press 15 through which molten lead 60 is forced by a rotating screw 61 to form the lead sheath 16 around the coated, insulated core 13. The forming die 56 is fitted into an internal bore provided in a die holder 63 secured on the end of the extruding apparatus by a nut 64. The nut 64 is provided with internal threads to receive a bushing 65 which holds the forming die 56 firmly in place in the die holder.

The lead press 15 (Fig. 1) may be of the type generally known as a "Pirelli" lead press, which is described fully on pages 310 to 423, inclusive, of the issue of the British publication "Engineering" published April 8, 1949, and the lead press 15 has been described only insofar as it is necessary for a complete understanding of the invention.

The sealing compound supplied to the inner tank 30 (Fig. 1) flows through the inner pipe 40 and thereby surrounds the cable 13 being advanced through the tank 30 and the pipe 40 to the lead extruding apparatus 15. The sealing compound discharges from the end of the pipe 40 and fills the annular clearance between the cable 13 and the core tube 55, between the pipe 40 and tube 48 and between the pipes 40 and 44. The compound flows from the annular clearance between the pipe 40 and the tube 48 through the pipe 44 and through an opening 46 (Figs. 1 and 4) provided in the flange 41 at the bottom of the pipe 40 into the outer tank 23, and thence into the duct 28. The viscosity of the coating compound and the size of the opening regulate the circulation of the compound through the pipes 40 and 44 so that the compound fills the space between the pipe 40 and the tube 48, and between the pipes 40 and 44 to the level of the compound in the tank 30. As the cable 13 advances through the tank 30 and the pipe 48, a coating of the compound adheres to the jacket 20 in a more or less irregular or uneven thickness. As the cable passes through the central opening of the core tube 55, the opening in the core tube smooths out the compound adhering to the jacket into a uniform and concentric coating 11. As the coated cable emerges from the die the lead 60 is extruded therearound to form the sheath 16.

The coating compound is supplied continuously to the tank 30 of the coating unit 10 at a rate sufficient to keep the cable surrounded thereby throughout its travel from the wiping block 37 to the central opening of the core tube 55 in order to obtain an even coating 11 on the cable 13. If the cable was not surrounded with coating compound until it passed through the core tube, the compound on the cable would flow to the bottom of the cable. As a result, the core tube would wipe off the excess compound on the bottom of the cable and leave an uneven coating on the cable.

The barrel 51, the tube 48, the core tube holder 50 and the core tube 55 are maintained at a tem-

perature sufficient to keep the lead 60 at an extrudable temperature. The coating compound may be of the type which must be heated so that it can be readily circulated through the coating unit 10. The coating compound is circulated from the tank 30 into the lead press 15 and from the lead press into the tank 23 and duct 28 at a sufficient rate of flow to prevent charring of the compound on the core tube 55 and the elongated tube 48.

Operation

The cable 13 is advanced continuously at a predetermined rate from a supply reel or directly from apparatus which extrudes the insulating jacket 20 on the core 18, and passes through the entrance opening 24 of the tank 23, the tank 30, the pipe 40 and the extrusion orifice 57 of the lead press 15. A suitable sealing compound, from which the coating 11 is formed, is supplied to the trough and discharged therefrom into the tank 30 at such a rate that it completely fills the tank 30 and circulates from the exit port 25 along the cable through the pipe 40 into the annular clearance between the pipe 40 and the elongated tube 48, and the annular clearance between the cable 13 and the core tube holder 50 and the core tube 55 of the lead press 15. The compound flows through the tube 48 and the pipe 44 into the outer tank 23 from which it flows into the duct 28 and returns to a supply tank (not shown) for the sealing compound.

As the cable enters the inner tank 30, the wiping block 37 cleans the surface of the jacket 20 so that any foreign substance on the jacket is removed before the cable enters the tank 30. The sealing compound in the tank 30 and in the pipe 40 surrounds the cable 13 completely, and the compound adheres to the jacket 20 of the cable. The movement of the cable 13 through the tank 30 serves to siphon the sealing compound from the tank into the pipe 40, whereby a substantial quantity of the compound discharges into the annular clearance between the cable 13 and the core tube holder 50 and the core tube 55. The compound piles up at the core tube 55, and as the cable 13 passes through the annular opening in the core tube, the core tube smooths the compound uniformly and concentrically on the cable. As the coated cable enters the extrusion orifice 57, the screw 61 extrudes the molten lead 60 into the form of a lead sheath 16 around the coated cable. This arrangement produces a substantially uniform coating 11 of compound between the jacket 20 and the lead sheath 16.

While the above-described apparatus is designed to coat a cable being advanced to a lead press, it may be readily modified to suit various types of filamentary articles and associated manufacturing apparatus without departing from the spirit and scope of the invention.

What is claimed is:

1. In a cable core covering apparatus including an elongated, tubular barrel through which a cable core to be covered may be advanced and a die at the exit end of said barrel for forming a sheath on the cable core, the improved applicator for applying liquid coating compound to the core which comprises a receptacle for receiving a continuous supply of liquid coating compound and having aligned entrance and exit ports through which the cable core is advanced, an inner elongated tube projecting from the receptacle in alignment with said ports so as to surround the advancing cable core, said tube being designed to

extend into the tubular barrel to a point adjacent to the die at the exit end of the barrel, a larger outer tube having one end thereof surrounding the initial portion of the inner tube which is positioned in said barrel, whereby liquid coating compound flows from the receptacle through the inner tube around the advancing cable core until the core reaches a point near the die and the excess coating compound flows out of the barrel in the opposite direction around the inner tube and through the outer tube, and means at the other end of the outer tube for conducting away the excess coating compound.

2. In a cable core covering apparatus including an elongated, tubular barrel through which a cable core to be covered may be advanced and a die at the exit end of said barrel for forming a sheath on the cable core, the improved applicator for applying liquid coating compound to the core which comprises a receptacle for receiving a continuous supply of liquid coating compound and having aligned entrance and exit ports through which the cable core is advanced, an inner elongated tube projecting from the receptacle in alignment with said ports so as to surround the advancing cable core, said tube being designed to extend into the tubular barrel to a point adjacent to the die at the exit end of the barrel, a plurality of spacers for supporting said tube concentrically within the tubular barrel, a larger outer tube having one end thereof surrounding the initial portion of the inner tube which is positioned in said barrel, said outer tube fitting closely within said barrel so as to prevent a leakage of liquid coating compound therebetween, whereby liquid coating compound flows from the receptacle through the inner tube around the advancing cable core until the core reaches a point near the die and the excess coating compound flows out of the barrel in the opposite direction around the inner tube and through the outer tube, and means communicating with the other end of the outer tube for conducting away the excess coating compound.

3. In a cable core covering apparatus including an elongated, tubular barrel through which a cable core to be covered may be advanced and a die at the exit end of said barrel for forming a sheath on the cable core, the improved applicator for applying liquid coating compound to the core which comprises a receptacle for receiving a continuous supply of liquid coating compound and having aligned entrance and exit ports through which the cable core is advanced, wiping means positioned adjacent to the entrance port in the receptacle for conditioning the surface of cable core prior to the application of the liquid coating compound, an inner elongated tube projecting from the receptacle in alignment with said ports so as to surround the advancing cable core, said tube being designed to extend into the tubular barrel to a point adjacent to the die at the exit end of the barrel, a larger outer tube having one end thereof surrounding the initial portion of the inner tube which is positioned in said barrel, whereby liquid coating compound flows from the receptacle through the inner tube around the advancing cable core until the core reaches a point near the die and the excess coating compound flows out of the barrel in the opposite direction around the inner tube and through the outer tube, and means external of the barrel communicating with the other end of the outer tube for conducting away the excess coating compound.

4. In a cable core covering apparatus including

an elongated, tubular barrel through which a cable core to be covered may be advanced and a die at the exit end of said barrel for forming a lead sheath on the cable core, the improved applicator for applying liquid coating compound to the core which comprises a receptacle for receiving a continuous supply of liquid coating compound and having aligned entrance and exit ports through which the cable core is advanced, an inner elongated tube projecting from the receptacle in alignment with said ports so as to surround the advancing cable core, said tube being designed to extend into the tubular barrel to a point adjacent to the die at the exit end of the barrel, a larger outer tube surrounding the initial portion of the inner tube which is positioned in said barrel, said outer tube fitting closely within said barrel so as to prevent a leakage of liquid coating compound therebetween, whereby liquid coating compound will flow from the receptacle through the inner tube around the advancing cable core until the core reaches a point near the die and the excess coating compound flows out of the barrel in the opposite direction around the inner tube and through the outer tube, and a drain positioned adjacent to the receptacle for receiving any coating compound overflowing the sides of the receptacle and communicating with the outer tube so as to drain the excess coating compound therefrom.

5. In a cable core covering apparatus including an elongated, tubular barrel through which a cable core to be covered may be advanced and a die at the exit end of said barrel for forming a sheath on the cable core, the improved applicator for applying liquid coating compound to the core which comprises a receptacle for receiving a continuous supply of liquid coating compound and having aligned entrance and exit ports through which the cable core is advanced, an inner elongated tube projecting from the receptacle in alignment with said ports so as to surround the advancing cable core, said tube being designed to extend into the tubular barrel to a point adjacent to the die at the exit end of the barrel, a plurality of spacers for supporting said tube concentrically within the tubular barrel, a larger outer tube having one end thereof surrounding the initial portion of the inner tube which is positioned in said barrel, said outer tube fitting closely within said barrel so as to prevent a leakage of liquid coating compound therebetween, a second plurality of spacers for supporting the inner tube concentrically within the outer tube, whereby liquid coating compound flows from the receptacle through the inner tube around the advancing cable core until the core reaches a point near the die and the excess coating compound flows out of the barrel in the opposite direction around the inner tube and through the outer tube, and means communicating with the other end of said outer tube for conducting away the excess coating compound.
